UNITED STATES PATENT OFFICE.

AARON H. WOLFF, OF NEW YORK, N. Y.

GAS-BURNER.

1,399,178.

Specification of Letters Patent.

Patented Dec. 6, 1921.

Application filed March 7, 1919. Serial No. 281,137.

To all whom it may concern:

Be it known that I, AARON H. WOLFF, a citizen of the United States, residing at the borough of Manhattan, in the city, county,

5 and State of New York, have invented certain new and useful Improvements in Gas-Burners, of which the following is a specification, reference being had therein to the accompanying drawings, which form a part 10 thereof.

My invention relates to gas burners, and more particularly to blue flame burners adapted for use in connection with gas stoves and heaters of various types.

15 Heretofore burners adapted for use in gas stoves, heaters, and lighting fixtures using mantles, have been of the well known Bunsen type, the structure thereof being modified to meet the particular conditions of use.

20 In burners of this type the common practice has been to discharge the gas from a pipe line into a mixing tube having air inlet ports adjacent the end of said pipe, so that air will be drawn into the mixing tube by the

25 gas flowing from the pipe, the mixing tube being so constructed that the volume of this air may be controlled in order to secure any desired admixture of gas and air. The mixing tube is in communication with a dis-

30 tributing chamber having a plurality of burner openings. Burners of this type, as a general rule, burn with a low blue flame and back firing through the distributing chamber to the tube is of frequent occurrence.

35 Furthermore, the flame from each jet is, as a rule, of small volume.

With these conditions in mind, the object of my invention is to provide a blue flame burner which will be so constructed as to not 40 only insure a long flame of large volume, but a substantially perfect combustion of the gas through the proper introduction of air at the point of ignition of the gas, without, however, developing excessively high 45 temperatures.

A burner made in accordance with my invention burns with a circular flame, combustion at the point of ignition of the gas, being supported in part by the atmospheric 50 air surrounding each burner jet, and in part by an auxiliary supply of atmospheric air introduced within the circular flame.

The inflammable mixture delivered to the 55 several burner jets is mixed with air, as in the ordinary Bunsen burner, the air supplied within the circular flame being for the pur-

pose, not of securing the desired mixture of gas and air, but for promoting combustion in a manner to develop a comparatively high flame having large volume.

60

The burner casing is so constructed, when a plurality of burner jets are used, as to insure the desired mixture of gas and air delivered to the casing and a proper distribution thereof amongst the several burner jets.

65

I have found in actual practice that back firing to the mixing chamber, or mixing tube through the jet openings is impossible, there being no necessity to use gauze, or other well known appliances, to prevent such back 70 firing.

The invention consists primarily in a gas burner embodying therein a mixing chamber, a mixing tube discharging thereinto, a gas supply pipe discharging into said mixing tube, and two concentric tubes of relatively different diameters, whereby a substantially circular jet is formed, one of said tubes communicating with said mixing chamber and the other of said tubes communicating with atmosphere, whereby air for supporting combustion is present on both sides of a circular flame; and in such other novel features of construction and combination of parts as are hereinafter set forth and 80 described, and more particularly pointed out in the claims hereto appended.

85

Referring to the drawings, Figure 1 is a view partly in section and partly in elevation, of a gas burner embodying my invention, adapted for use with a gas heater;

90

Fig. 2 is a plan view thereof with the mixing tube removed; and

Fig. 3 is a section on the line 3—3 upon 95 an enlarged scale.

Like letters refer to like parts throughout the several views.

In the embodiment of my invention shown in the drawings, I employ a casing *a* forming a mixing and distributing chamber for the inflammable gas mixture. Carried by said casing *a* are two concentric, vertical tubes *b* and *c*, the tube *c* being slightly smaller in diameter than the tube *b* so that a 100 circular burner jet opening *d* is formed at the upper ends of said tubes.

105

The tube *b* communicates with the chamber *a*, while the tube *c* extends through said chamber and has an open bottom communicating with atmosphere. A mixture of air and gas is delivered to the chamber *a*

110

through the mixing tube *e* provided with the usual air regulator *f*, gas being delivered to said tube through the gas pipe *g*, the valve *h* arranged in said pipe controlling the flow of gas to the burner. To insure a proper admixture and distribution of the gas throughout the mixing chamber within the casing *a*, I extend said casing on one side of the tubes *c* adjacent the inlet of the mixing tube *e*, to form an enlarged portion *i* of the casing extending adjacent each of the burner jet openings *d*. The casing *a* is closed except as to these jet openings.

The tubes *b* preferably terminate at a point substantially flush with the adjacent interior wall of the casing *a*, and are, in the form of the invention shown, of a length of substantially one-half inch so that the jet opening *d* of each burner will be of sufficient length and sufficiently narrow (approximately $\frac{1}{2}$ of an inch in the form of the invention shown), to insure the delivery of a sufficient volume of gas at the top of the nozzle to maintain a flame of the desired volume and height, while preventing the flame following the gas through said jet opening to the mixing chamber and the mixing tube. I have found that in a burner made in accordance with the drawings, the rate of flow of the gas through the burners is apparently higher than that of the propagation of flame within said openings, and that it is impossible, by either varying the rate of flow of the gas to the mixing chamber, or by varying the mixture in said chamber, to cause a back firing through these jet openings, notwithstanding that no gauze or other material is used in the structure.

The brackets *j*—*j'* are used merely to mount the burner in a desired relation to a stove, heater, or other appliance in connection with which the burner is used.

The operation of the herein described gas burner is substantially as follows:

When starting the burner, the valve *h* is opened to permit the flow of gas through the pipe *g* into the mixing chamber, this gas being mixed with atmospheric air as it flows through the mixing tube *e*. The richness of the mixture is controlled by the regulator *f* in the usual manner. As the inflammable mixture enters the enlarged portion *i* of the casing *a*, it flows the entire length thereof without impinging upon any of the several tubes *c* in a manner to interfere with the free flow of gas or a proper distribution of the gas throughout the mixing chamber within the casing *a*. Gas from the mixing chamber flows through the several jet openings *d* and is ignited at the tops of the tubes *b* and *c*.

After the ignition of the gas at the discharge end of the jet openings *d*, combustion at said jet openings will be supported in part by the air surrounding the tubes *b* and in part by a current of air flowing

through the tubes *c*, the circulation of air through said tubes, induced by convection, developing a flame three or four inches in length, which flame is substantially circular. The flow of the air through the tube *c*, however, is not at a sufficiently high rate to develop excessively high temperatures in the flame, so that the burner may be used in the same manner as the ordinary Bunsen burner, in gas stoves, heaters, etc. The temperature developed by the flame, however, is considerably higher than the ordinary burner flame, the color of the flame being whiter than with the ordinary Bunsen burner.

The air passing through the tubes *c* assists materially in a complete combustion of the gas passing through the opening *d*, the stoppage of this opening having the instant effect of shortening the length of the flame and at the same time deepening its color.

In a burner made in accordance with my invention, the air supplied through the tube *c* is solely for the purpose of aiding the combustion of a mixture of gas and air and in no sense contributes toward, or modifies, the richness of the mixture.

In a burner made in accordance with my invention, higher efficiency may be secured than with the ordinary Bunsen burner, and there is the further advantage that in the use of the burner there is no possibility of back firing through the jet openings to the mixing chamber or the mixing tube, which, though not dangerous, is annoying.

While, in the accompanying drawings I have shown a burner in which the jet openings are circular and arranged in a straight line, it is apparent that the configuration of said openings and of the mixing chamber is immaterial to the invention, and may be modified indefinitely to adapt it to different stove or heater structures in connection with which the burner is to be used.

The gas used in a burner made in accordance with my invention, may be at the pressure of the ordinary service pipe and no special mechanism is required for developing and maintaining a desired circulation of air through the pipes *c*.

It is not my intention to limit the invention to the precise details of construction shown in the accompanying drawings, it being apparent that such may be varied without departing from the spirit and scope of the invention.

Having described the invention, what I claim as new and desire to have protected by Letters Patent, is:

1. A gas burner embodying therein a casing forming a mixing and distributing chamber, a plurality of short tubes communicating with and projecting from the top of said casing, a plurality of tubes extending vertically through said casing, beyond the top thereof and within said short tubes,

being conterminous therewith, whereby an elongated jet opening is formed between each of said long and each of said short tubes, said long tubes opening to atmosphere below said casing, said casing having an enlarged portion at one side of said long tubes, a mixing tube discharging into one end of said enlarged portion and in substantially axial alinement therewith, whereby the incoming combustible mixture has an unobstructed passage to adjacent each of the burners, and a gas supply pipe discharging into said mixing tube.

10 2. A gas burner embodying therein a casing forming a mixing and distributing chamber, a plurality of tubes extending vertically through said casing and beyond the top thereof, a plurality of short tubes inclosing the projecting ends of said other tubes, 15 said short tubes communicating with the interior of said casing through a narrow open-

ing between same and said first named tubes, whereby an elongated jet opening between said tubes is formed, and back firing therethrough to said mixing chamber is prevented, said casing being extended on one side of said first named tubes, a mixing tube discharging into said extended portion of said casing and in substantially axial alinement therewith, whereby the incoming combustible mixture has an unobstructed passage to adjacent each of the burners, and a gas pipe discharging into said mixing tube.

10 25 In witness whereof I have hereunto affixed my signature, this 5th day of March, 1919, in the presence of two subscribing witnesses.

AARON H. WOLFF.
